CLAMPING BAR FOR A PAPER CLIP

Abe Elenowitz, Flushing, N. Y.

Application January 25, 1956, Serial No. 39,912

Term of patent 3½ years

(Cl. D74—1)

Fig. 1

Fig. 2

Fig. 3

Fig. 4

Fig. 1 is a front elevational view of a clamping bar for a paper clip, showing my new design;

Fig. 2 is a cross sectional view thereof taken on line 2—2 of Fig. 3 and looking in the direction of the arrows;

Fig. 3 is a top plan view thereof; and

Fig. 4 is a side elevational view with parts thereof being shown broken away for convenience of illustration.

I claim:

The ornamental design for a clamping bar for a paper clip, as shown and described.
